Primary Examiner—Alan P. Douglas*Assistant Examiner*—S. Snapp*Attorney, Agent, or Firm*—Lerner, David, Eisenberg, Krumholz & Mentlik[57] CLAIM

The ornamental design for a base for displaying or holding items, as shown and described.

DESCRIPTION

FIG. 1 is a perspective view of the base in accordance with my new design;

FIG. 2 is a front elevational view thereof;

FIG. 3 is a rear elevational view thereof;

FIG. 4 is a side elevational view thereof;

FIG. 5 is a bottom plan view thereof; and,

FIG. 6 is a top plan view thereof.

The dashed line representations of a paperclip holder in the shape of a medicinal inhaler as shown in FIGS. 1-6 are for illustrative purposes only and do not form any part of the claimed design. In the preferred embodiment, the base is used as a promotional item for pharmaceutical and medical devices.
